UNITED STATES PATENT OFFICE.

GEORGE R. CORNWALL, OF RYE, NEW YORK, ASSIGNOR TO AMERICAN PLANOGRAPH CO.,
OF NEW YORK, N. Y., A CORPORATION OF WEST VIRGINIA.

PRINTING-PRESS.

No. 926,102.

Specification of Letters Patent.

Patented June 29, 1909.

Application filed May 27, 1903, Serial No. 158,961. Renewed October 23, 1905. Serial No. 284,035.

To all whom it may concern:

Be it known that I, GEORGE R. CORNWALL, a citizen of the United States, residing at Rye, in the county of Westchester and State 5 of New York, have invented certain new and useful Improvements in Printing-Presses, of which the following is a specification.

The invention relates to printing presses and more especially to those in which one 10 member, or both, of a printing couple are mounted for rotary motion.

In certain aspects of the invention it relates to presses in which a printing surface consists of, or is carried upon, a flexible 15 plate, which may be of metal, mounted upon a cylinder constituting one of the members of a printing couple; in other aspects, however, the invention is applicable to presses using other kinds of plates.

20 The invention has for an object the protection of printing surfaces carried on the press, in order to effect the longevity of the plate and to produce impressions of a superior quality.

25 Objects of the invention, more particularly, are to provide against abrasion or attrition, or other injury to the printing surfaces, by reason of the said surfaces coming in contact with the opposed surface in the 30 printing couple at the line of impression contact in the absence of an impression-receiving material between the surfaces at the said line of impression contact, whether the said opposed surface be a printing surface 35 or an impression surface merely; to prevent injury to the printing surface by crushing or indenting, or otherwise, by reason of variations in the thickness of the plates or of the impression-receiving material, or of undue 40 thickness, or other improper condition of the impression-receiving material; to equalize the impression by eliminating variations in the impression due to varying thicknesses of the plates or the impression-receiving material 45 in different parts.

These and other objects of invention will in part be obvious and will in part more fully appear hereinafter.

The invention therefore contemplates the 50 providing of means for causing the surfaces of the printing couple to instantly separate when the paper or other impression-receiving

ing material fails from any cause whatsoever between the surfaces of the printing couple at the line of impression contact while 55 a printing plate is present at the line of impression contact; the invention further contemplates the providing of means for permitting the plate or support for the printing surface, when same is of a flexible or elastic 60 material, to yield in any part where the plate or the impression-receiving material may vary slightly in thickness or where the sheet or web of impression-receiving material is presented folded over, unduly thick, 65 or otherwise in improper condition. Such yielding action of the plate will also tend to render uniform the degree of contact-pressure or "squeeze" between the surfaces of the printing couple despite small local 70 variations in the thickness of the plate or of the impression-receiving material which would otherwise produce an obvious effect in the printed impression.

The invention consists in the novel parts, 75 improvements and combinations herein shown and described.

The invention is well adapted for application to, or embodiment in, presses used for planographic printing and carrying printing plates in the form of flexible metal sheets suitable for planographic printing, such as those of zinc or aluminum. As it is possible with planographic plates to oppose two printing surfaces in one printing couple 85 and thus perfect a sheet or web with but one pair of cylinders, each cylinder acting as both a form and impression cylinder, the invention has been illustrated as applied to, or embodied in, a press of this character. It 90 will be understood however, and as hereinbefore indicated, that in many of its aspects the invention is applicable to other forms of presses.

The accompanying drawings, referred to 95 herein and forming a part hereof, illustrate one embodiment of the invention, the same serving in connection with the description herein to explain the principles of the invention.

Figure 1 represents a plan view of a printing press; Fig. 2 is a side elevation; Fig. 3 is a similar view to Fig. 2, showing parts of the machine in a different position;

Fig. 4 is a sectional elevation of the machine, taken on line 4—4 of Fig. 2; and Fig. 5 is a detail view showing the escapement lever in position to arrest the cam shaft at the completion of a rotation.

In the illustrated embodiment; 1 represents the framework of the machine, which may be of any desirable or convenient form. Suitably mounted in said framework is 10 shown a printing couple in the form of two rotary cylinders 2, 2, upon either or both of which is mounted a printing face or plate 3, which carries the design to be printed. In accordance with some features of the invention it is immaterial how many plates are used or how they are mounted; in accordance with other features, however, it is contemplated to mount plates upon each cylinder and in opposition to each other, so that 15 a single couple will perfect a sheet or web. Said cylinders are mounted to rotate in suitable bearings supported in the frame of the machine. Means for holding the members of the printing couple normally to impression contact are provided, said means being constructed and arranged to permit relative movement of the said members so as to allow them to pass into or out of impression contact, for the purposes hereinafter 20 set forth. In the illustrated form of such means the bearings of one of said cylinders are shown carried in movable journal-boxes 4, slideable in ways 5 in the frame of the machine, and a spring 6 bears at one of its ends upon a journal-box and at its other end bears against a fixed part of the machine, such as the end wall of one of the ways above referred to. Said springs 6 tend to hold the 25 cylinders to impression contact but will, under proper conditions, permit movement of their cylinder away from impression contact, as hereinafter set forth. Any suitable form of impression-receiving material may be used, and also any suitable or convenient feeding means therefor. One convenient 30 form of such means is shown in the drawings as comprising a web of paper 7 suitably supported on the press frame in the form of a roll and led or interposed between the cylinders 2 at the line of impression contact for the purpose of receiving the impression. Driving means for the press of any desirable or convenient form are 35 provided, and in the illustrated form intermeshing gears are secured to the shafts of said cylinders to cause their rotation at the same peripheral speed. Said cylinders are further shown as driven from a suitable gear 8 journalized in the frame of the machine and having formed thereon a belt pulley 9, driven by suitable belt connection with a 40 source of power. Inking mechanism is provided for the press, and may be of any form found convenient or desirable. As in the 45 illustrated embodiment each of the cylinders 50

comprised in the printing couple is shown carrying a printing plate, as hereinafter more fully described, each of said cylinders 2, 2, is shown as being provided with inking rollers 10, 10, which are inked by transfer 55 inking rolls 11, 11, mounted on oscillating arms 12, 12, pivoted at their lower ends upon the frame of the machine. Said transfer inking rolls carry a supply of ink to the rolls 10, 10, from ink fonts 13, 13, supported on 60 the frame of the machine and supplied with the usual ink delivery rolls 14, 14, and blades 15, 15. As in the illustrated embodiment the press is shown as equipped with planographic plates, damping mechanism is also 65 provided. Said damping mechanism likewise may be of any form found convenient or desirable. As herewith shown, each cylinder is provided with suitable dampening rolls 16, 16, which are supplied in a 70 similar manner with water from water fonts 17, 17.

The invention contemplates, as one of its features, as hereinbefore indicated, the providing of means for securing a high quality 75 of impression notwithstanding slight differences of thickness in various parts of the printing plate, or plates, or in the impression-receiving material, and for preventing injury to the plates, or the printing surfaces, 80 or the design, by crushing, indenting, or otherwise, consequent upon improper condition of the impression-receiving material from the causes hereinbefore enumerated or from other causes. A form of such means 85 is shown in the illustrated embodiment, wherein the printing surfaces are shown as consisting of, or as being carried by a flexible plate 3 mounted upon a cylinder 2. Interposed between the plate and the surface 90 of the cylinder is an elastic or yielding material, preferably in the form of a layer 18. The particular material employed for this purpose forms no part of my invention, and may be any suitable material such as a rubber blanket or cushion composed of rubber, 95 felt, or a felt and rubber composition. The plate 3 may be mounted upon the cylinder by suitable holding and stretching devices herein indicated as clamps 39, constructed 100 and arranged to have the required combined holding and stretching action. So far as the aspect of the invention just indicated is concerned, it is immaterial what the properties 105 of the backing material and of the clamps are as concerns the conduction of electricity, but in other aspects of the invention the use of a form of means is contemplated comprising a plate insulated from the cylinder, and it may therefore be found convenient to have the layer 18 of non-conducting, or insulating, 110 as well as yielding, or elastic, material and also to have the clamps with insulated, or non-conducting, mountings or contacts. 115 The invention has in view also the protec- 120

tion of the printing surfaces from damage or destruction by abrasion, or attrition, or otherwise, by reason of a plate contacting with, or rotating against the opposed surface in the printing couple, whether such opposed surface be another plate, or only an impression surface. Means have been provided, therefore, by the invention for instantly moving the surfaces of the printing couple 10 out of impression contact when the paper or other impression-receiving material fails, from breakage or other cause, between the said surfaces of the printing couple at the line of impression contact while a printing 15 plate is present at the line of impression contact. In the form of such means illustrated in the present embodiment, one of the cylinders 2 is shown mounted in bearings 20 slidable in the frame 1, as hereinbefore set forth. Toggles 19, 19, are secured at one of their ends to the slidable journal-boxes of said cylinder and at their other ends are connected to the stationary frame 1 of the machine. To the knuckle joints of said toggles 25 are pivoted links 20, the lower ends of which are pivotally connected with arms 21. Said arms 21 are pivoted to the frame of the machine and may, if desired, carry at their outer ends can rollers 22. Said can rollers engage with cams 23 on a cam shaft 24, mounted transversely of the machine. Secured on said cam shaft 24 is a one-tooth 30 escapement 25 coöperating with an escapement lever 26 pivotally mounted upon the frame of the machine. Mounted loosely 35 upon said cam shaft 24 is shown a gear 27, connected to the shaft 24 by a suitable friction clutch or disk 27^a which places the shaft 24 under a tendency to rotate in the direction of the arrow in Fig. 2, the shaft being 40 normally held at rest, however, by means of the escapement lever 26. Said gear 27 is driven by suitable means, and is herein shown as being driven through the medium 45 of a transmission gear 28 in mesh therewith and having suitable driving connections with the cylinder 2 in stationary bearings. The outer end of the arm 26 is formed with an armature 29 arranged adjacent an electromagnetic device 30, energized by connections 50 from a source of electrical energy such as a battery 31.

Means are provided for making or breaking the electrical circuit so that it may control the governing device for the mechanism which acts to cause the cylinders to pass into and out of impression contact at such time and in such manner as to cause the printing couple to pass out of impression contact with a printing plate is present at the line of impression contact in the absence of an impression-receiving material at the said line of impression contact. The form of such means included in the present embodiment comprises devices by which the

printing plate or plates are brought into the circuit and the presence of the impression-receiving material between the surfaces of the printing couple while a plate is present at the line of impression contact will 70 serve to maintain a gap in the circuit, but upon a plate reaching the line of impression contact in the absence of the impression-receiving material it will, by contacting with the opposed face of the printing couple 75 close the circuit and cause the magnet 30 to actuate the lever 26, which may be regarded as a governing device, to release the throwing-off mechanism and thus permit the surfaces of the printing couple to immediately 80 pass out of impression contact. The devices for bringing the plates into the circuit comprise arms 32, 32; 33, 33, which are pivotally mounted upon the frame of the machine and are insulated therefrom by the insulation 85 36, 36. The rollers 34, 34; 35, 35, of said arms are maintained in contact with the printing surfaces of said cylinders by means of springs 37, 37, and their points of contact are above and below the line of contact of 90 the cylinders. The armature 29 is normally held away from the electromagnetic device 30 by means of a spring 38. As in the form of means for controlling the relation of the surfaces of the printing couple with respect 95 to the presence or absence of the impression-receiving material while a printing plate is passing the line of impression contact the printing plates are insulated from the cylinder, the clamping and stretching devices 39 100 for the plates are also adapted to coöperate in the insulation of the plates. In this embodiment the contact portion of the jaws are of insulated material and serve to hold the plate against a strip 40 of insulating material.

The operation of the mechanism herein shown and described is as follows: Upon suitable connections of the driving gear 8 with a source of power the cylinders 2, 2, are rotated in opposite direction through their intermeshing gears, and a web or sheet of paper 7 is fed between the cylinders. The printing surfaces are carried around by rotation of the cylinders beneath the dampening and inking rolls and the inked design or printing is impressed upon opposite sides of the sheet or web. As long as the sheet or web of paper is between the cylinders the action of the springs 6 causes said cylinders to be maintained in printing contact therewith, with pressure sufficient to cause the impressions to be transferred from the printing faces of the cylinders simultaneously to both sides of the sheet or web. Should a break in the web or sheet occur, or should, for any reason, a sheet fail to be fed between the cylinders, a momentary contact between printing faces would occur. This momentary contact closes the electrical cir- 130

cuit and the electromagnetic device 30 becomes energized. Armature 29 is then attracted, thereby overcoming the action of spring 38. The movement of the armature 29 toward the electromagnetic device causes an escapement of the cam shaft 24 by releasing the escapement lever 26 from the escapement tooth 25; said shaft being thus released is caused to rotate through the medium of friction gear 27 and transmission gear 28. The rotation of said shaft 24 carries with it the cam 23 which passing under the cam roller 22 raises the arm 21; thereby through the medium of the link 20 straightening the toggle 19, moving one of the cylinders 2 away from its companion cylinder, and preventing any contact between the printing surfaces of the cylinders. The cam 23 will hold the cylinders 2, 2, apart until its low part comes below the cam roller 22. As soon as the cylinders are thrown apart the electrical circuit is broken and lever 26 drops into position to catch tooth 25.

From all the foregoing it will be understood that mechanism has been provided which realizes the objects and advantages herein set forth as well as other objects and advantages.

The invention, in its broader aspects, is not limited to the particular constructions shown, nor to any particular constructions by which it has been or may be carried into effect, as many changes may be made in the construction without departing from the main principles of the invention and without sacrificing its chief advantages.

Having thus described my invention, the following is what I claim as new therein and desire to secure by Letters Patent:—

1. A printing press having in combination a cylinder mounted for rotary motion, a flexible metal printing plate mounted on said cylinder, means for holding the plate upon the cylinder while electrically insulating it therefrom, a source of electrical energy in circuit with the plate, a movable member upon the press controlled by the said circuit, a layer of yielding material interposed between the printing plate and the surface of the cylinder, and a member adapted to co-act with said cylinder to form a printing couple.

2. A printing press having in combination a cylinder mounted for rotary motion, a metal printing plate mounted on said cylinder, means for holding the plate upon the cylinder while electrically insulating it therefrom, a source of electrical energy in circuit with the plate, a movable member upon the press controlled by the said circuit, and a member adapted to co-act with the said cylinder to form a printing couple.

3. A printing press having in combination a cylinder mounted for rotary motion, a metal printing plate mounted on said cylinder, means for holding the plate upon the

cylinder while electrically insulating it from the cylinder, an insulating material interposed between the printing plate and the surface of the cylinder so as to insulate the plate from the cylinder, a source of electrical energy in circuit with the said plate, a movable member upon the press controlled by the said circuit, and a member adapted to coact with said cylinder to form a printing couple.

4. A printing press having in combination a cylinder mounted for rotary action, a flexible metal printing plate mounted on said cylinder, means for holding the plate upon the cylinder while electrically insulating it from the cylinder, a layer of yielding and insulating material interposed between the printing plate and the surface of the cylinder, a source of electrical energy in circuit with the said plate, a movable member upon the press controlled by the said circuit, and a member adapted to coact with said cylinder to form a printing couple.

5. A printing press having in combination a cylinder mounted for rotary motion, a flexible metal printing plate mounted on said cylinder, a layer of insulating material interposed between the printing plate and the cylinder, holding and stretching means for the plate mounted upon the cylinder, said holding and stretching means being constructed and adapted to insulate the plate and press from each other, a source of electrical energy in circuit with the said plate, a movable member upon the press controlled by the said circuit, and a member adapted to coact with said cylinder to form a printing couple.

6. A printing press having in combination two members constituting a printing couple, a printing plate mounted on one of said members, the plate being insulated from the said member, the other member of the printing couple having an insulated portion arranged so as to oppose said printing plate when at the line of impression contact, the said printing plate on one member and the said insulated portion on the other member being arranged in an electrical circuit, so that they will operate to contact with each other and close the circuit if they reach the line of impression contact without a web or sheet of intervening impression-receiving material.

7. A printing press having in combination two members constituting a printing couple, one of said members carrying a printing plate, and means called into action by the absence of an impression-receiving material at the line of impression contact while the printing plate is passing the line of impression contact for moving one of the members of the printing couple away from impression contact.

8. A printing press having in combination two members constituting a printing

couple, said members being relatively movable into and out of impression contact, one of said members carrying a printing plate, and means called into action by the absence 5 of an impression-receiving material at the place of impression contact for moving or holding said members apart at all times when a printing plate is present at the line of impression contact in the absence of the 10 impression-receiving material.

9. A printing press having in combination two members constituting a printing couple, one of said members carrying a printing plate, one of said members being 15 movable toward and from the other member so as to establish or break impression contact, means for holding the said last-mentioned member to impression contact, and means called into action by the absence of 20 an impression-receiving material at the line of impression contact while the printing plate is passing the line of impression contact for moving the said movable member away from impression contact.

25 10. A printing press having in combination a pair of cylinders constituting a printing couple, a printing plate carried on one of said cylinders, one of said cylinders being movable into and away from impression 30 contact, and means, called into action by the absence of an impression-receiving material at the line of impression contact while the printing plate is passing the line of impression contact, for moving the said movable 35 cylinder away from impression contact while the printing plate is passing the line of impression contact.

11. A printing press having in combination two members constituting a printing 40 couple, said members being relatively movable into and out of impression contact, a printing plate carried by one of said members, means for causing relative movement of said members out of impression contact, 45 a governing device for the said means, an electrical circuit for controlling the said governing device, said circuit and device being arranged so that the said means will cause the printing couple to pass out of impression contact when the printing plate is 50 present at the line of impression contact in the absence of the impression-receiving material at the said line of impression contact.

12. A printing press having in combination two members constituting a printing couple, said members having relative movement into and out of impression contact, a printing plate carried by one of said members, means for holding the said members to 55 impression contact so as to print upon an interposed impression-receiving material, an electrical circuit adapted to be effected by the presence or absence of the impression-receiving material while the printing plate 60 is passing the line of impression contact, and

means controlled by said electrical circuit for causing relative movement of said members out of impression contact when a printing plate is at the line of impression contact in the absence of the impression-receiving material. 70

13. A printing press having in combination two opposed cylinders forming a printing couple, one of said cylinders being mounted in a slidable bearing, means for 75 normally holding the said cylinder to impression contact with the other cylinder, a toggle mounted between the slidable bearing and a fixed part of the press, a cam for controlling the toggle, a device for governing 80 the cam constructed and adapted to bring the said cam and toggle into action to throw off the press when the surfaces of the two cylinders come into contact without an intervening impression-receiving material. 85

14. A printing press having in combination two opposed cylinders forming a printing couple, one of said cylinders being mounted in a slidable bearing, means for 90 normally holding said cylinder to impression contact with the other cylinder, a toggle mounted between the slidable bearing and a fixed part of the press, a cam for controlling the toggle, a device for controlling the cam, and an electrical circuit for governing the 95 controlling device for the cam, said circuit being so arranged as to be energized when the surfaces of the two cylinders come into contact without an intervening impression-receiving material. 100

15. A printing press having in combination two opposed cylinders constituting a printing couple, a planographic printing plate mounted upon each of said cylinders, so as to perfect an intervening sheet or web, 105 and means for throwing said cylinders out of impression contact, said means being automatically actuated whenever the said plates reach the line of impression contact without the presence of an intervening sheet or web.

16. A printing press having in combination a printing couple comprising two opposed members each carrying a planographic printing surface, one of said printing surfaces consisting of, or being carried 115 upon, a flexible plate, means for holding said plate upon one of the said members of the printing couple so as to insulate the said plate from the said member, and a layer of elastic or yielding material interposed between the said plate and its supporting member, a source of electrical energy in circuit with said plate and a movable member upon 120 the press controlled by said circuit. 125

17. A printing press having in combination two opposed cylinders constituting a printing couple, a planographic printing surface carried on each of said cylinders, one of said printing surfaces consisting of, 130

- or being carried upon, a flexible plate, means for holding the said plate upon its cylinder so as to insulate said plate from said cylinder, and a layer of elastic or yielding material interposed between the plate and the surface of its cylinder, a source of electrical energy in circuit with said plate and a movable member upon the press controlled by said circuit.
18. A printing press comprising a pair of printing faces, a yieldable backing for one or both of said faces, means to bring said faces simultaneously into printing contact with opposite sides of a sheet or web of paper, and automatically-operated means to separate said faces on any contact occurring between them.
19. A printing press comprising a pair of cylinders, a printing face secured in each of said cylinders, a yielding backing between one or both of said printing faces and its cylinder, means to bring said printing faces simultaneously into printing contact with opposite sides of a sheet or web of paper, and means automatically operated to move said cylinders apart upon any contact occurring between their printing faces.
20. A printing press comprising a pair of cylinders, one of said cylinders mounted in fixed bearings, and the other of said cylinders having bearings movable toward and from the first-named cylinder, a printing face on each of said cylinders, a yieldable backing for one or both of said printing faces, means to bring said printing faces simultaneously into printing contact with opposite sides of a sheet or web of paper, and means automatically operated to move the cylinder having movable bearings away from the other cylinder upon any contact occurring between said printing faces.
21. A printing press comprising a pair of rotary cylinders, each of said cylinders having a printing face secured thereon and electrically insulated from said cylinders, means to bring said printing faces simultaneously into printing contact with the opposite sides of a sheet or web of paper, electrically-operated means in circuit with said printing faces, and means controlled by said electrically-operated means to move said cylinders apart on any contact occurring between their printing faces.
22. A printing press comprising a pair of cylinders, one of said cylinders mounted in stationary bearings, and the other of said cylinders mounted in bearings movable toward and from the other cylinder, each of said cylinders provided with a printing face, means to bring said printing faces simultaneously into printing contact with opposite sides of a sheet or web of paper, a shaft having a cam thereon, connections between said cam and the said movable bearings whereby said cam moves the cylinder
- having movable bearings away from the other cylinder, and automatic means to operate said cam upon the printing faces of said cylinders coming into contact.
23. A printing press comprising a pair of cylinders, each of said cylinders provided with a printing face, one of said cylinders having fixed bearings and the other of said cylinders having bearings movable toward and from the first-named cylinder, means to bring the printing faces simultaneously into printing contact with opposite sides of a sheet or web of paper, a toggle connected with said movable bearings, a cam and cam-lever, the operation of said cam controlled by the rotation of the cylinders, connections between said cam-lever and the toggle, an escapement controlling the movement of said cam, and automatic means for operating said escapement upon any contact occurring between the printing faces.
24. A printing press comprising a pair of cylinders, one of said cylinders mounted in stationary bearings and the other of said cylinders mounted in bearings movable toward and from the other cylinder, each of said cylinders provided with a printing face, means to bring said printing faces simultaneously into printing contact with opposite sides of a sheet or web of paper, a shaft having a cam thereon, connections between said cam and the said movable bearings, whereby said cam moves the cylinder having movable bearings away from the other cylinder, and electrically-operated means to control the operation of the cam and cause the same to operate on the printing faces coming into contact.
25. A printing press comprising a pair of cylinders, each of said cylinders provided with a printing face, one of said cylinders having fixed bearings and the other of said cylinders having bearings movable toward and from the first-named cylinder, means to bring the printing faces simultaneously into printing contact with opposite sides of a sheet or web of paper, a toggle connected with said movable bearings, a cam and cam-lever, the operation of said cam controlled by the rotation of the cylinders, connections between said cam-lever and the toggle, an escapement controlling the movement of said cam, and electrically-controlled means for operating said escapement when the faces of said cylinders come into contact.
26. A printing press including in combination two members constituting a printing couple, said members being relatively movable into and out of impression contact, one of said members having a printing surface, and detector means acting within the place of impression for tripping the impression, said means being called into action by the failure of the impression-receiving material at the place of impression.

27. A printing press having in combination two members constituting a printing couple, said members being relatively movable into and out of impression contact, one of said members carrying a printing plate, and means called into action by the absence of the impression-receiving material

at the place of impression contact during the impression for holding the members of the couple away from impression contact. 10
